UNITED STATES PATENT OFFICE.

HENRY W. FISHEL, OF NEW YORK, N. Y.

JEWELRY AND METHOD OF MANUFACTURING THE SAME.

1,425,188.

Specification of Letters Patent. Patented Aug. 8, 1922.

Application filed June 11, 1921. Serial No. 476,797.

To all whom it may concern:

Be it known that I, HENRY W. FISHEL, a citizen of the United States, and a resident of the borough of Manhattan, city, county, and State of New York, have invented certain new and useful Improvements in Jewelry and Methods of Manufacturing the Same, of which the following is a specification.

10 My invention relates to methods of manufacture of jewelry and more particularly to methods of manufacture of articles of jewelry having surrounding galleries. This invention is a modification of my two earlier 15 inventions described and claimed in Patents Nos. 1,361,704 and 1,361,705, of December 7, 1920.

The objects of my invention are to simplify 20 the manufacture of such articles of jewelry and to greatly reduce their manufacturing cost. A further object is the production of articles of jewelry having fancy or ornamented galleries, in combination with filigree ornamentation. A further object of 25 my invention is the production of articles of jewelry having greater strength and beauty than the saw-pierced articles of jewelry heretofore made. Other objects and advantages of my invention will hereinafter appear in the following description.

I will now describe the embodiment of my invention illustrated in the accompanying drawing and will thereafter point out my invention in claims.

35 In the drawing I have shown my invention as applied to the manufacture of a bar pin, but it is equally adapted to the manufacture of many other articles of jewelry.

Figure 1 is a face view of a block or bar 40 of metal adapted to be worked into an article of jewelry.

Figure 2 is a face view of the bar of metal after the stamping operation.

Figure 3 is a face view of the body of the 45 article of jewelry after the trimming or cutting operation.

Figure 4 is a face view of a bridging portion used in connection with my invention.

Figure 5 is a face view of the body of an 50 article of jewelry surrounded by the bridging portion.

Figure 6 is a face view of a gallery used in connection with my invention.

Figure 7 is a side view of the same.

55 Figure 8 is a face view of the completed article of jewelry.

Figure 9 is a side view of the same.

Figure 10 is a cross-section of the same taken on the line 10—10 of Figure 9.

Figures 11, 12, 13 and 14 are face view of 60 various forms of bridging portion adapted to be used in connection with my invention.

My method of manufacturing jewelry comprises four main operations, which are: first, a stamping operation; second, a trimming or cutting operation; third, the operation of fitting the bridging portion over the body of the article and soldering or welding it thereto; and fourth, the operation of fitting the gallery over the bridging portion 70 and soldering or welding it thereto. It is also possible to combine the stamping and cutting operation into a single operation, if desired.

In carrying out my invention, I take a 75 block of suitable metal and place it in a stamping press containing a die shaped to form the body of the article desired to be manufactured. The block of metal 1 is then stamped and the body 2 of the jewelry 80 article having a margin 3 of waste metal surrounding it is formed as is shown in Figure 2. I next cut the body 2 from the surrounding margin 3 of waste metal with a cutting die having the same contour as the stamping 85 die. The body 2 is thus completely formed and separated, and as thus formed and separated is shown in Figure 3.

In the manufacture of galleried jewelry, such as that shown and described in my two 90 patents above referred to, a space is provided between the gallery and the body resembling saw-piercing. In the present invention I take advantage of this space by providing in place thereof a metal ribbon 95 crimped to resemble filigree work, usually seen only in high grade handmade platinum jewelry. This crimped metal ribbon 6 which is shaped to conform to the contour of the body 2, but is of slightly greater perimeter

than the body 2, is placed around the body 100 2 and soldered or welded to it. A gallery 7 of the same general shape and contour as, but of slightly greater perimeter than the body 2 and surrounding crimped metal ribbon 6, is next placed around the ribbon 6 and soldered or welded to it. The gallery 105 7 consists of a narrow strip of metal and it may have a beveled upper portion 8 forming a sharp or knife edge. The gallery may 110 be ornamented if desired. The crimped metal ribbon 6 acts as a bridging portion

between the body 2 and the gallery 7. The ribbon is usually so crimped that the contacting points thereof contact alternately with the body and the gallery; that is, one point of the ribbon will be in contact with and secured to the body, and the adjoining point will be in contact with and secured to the gallery. This distribution of points of contact lends to the strength of the completed article. The ribbon 6 which is made of very thin metal can be so crimped that it takes up very little space when surrounding the body 2, and gives the appearance of very delicate filigree work which is obtainable only in very fine handwork.

It is obvious that the various modifications may be made in the construction shown in the drawing and above particularly described within the principle and scope of my invention:

I claim:

1. An article of jewelry comprising a body portion, a crimped metal ribbon surrounding the body portion, a gallery surrounding the crimped metal ribbon, the crimped metal ribbon acting as a bridging portion between the body and the gallery.
2. An article of jewelry comprising a

body portion, a gallery surrounding the body portion, a crimped metal ribbon placed between the body and the gallery and secured to the body at certain points and to the gallery at other points.

3. An article of jewelry comprising a body portion, a gallery surrounding the body portion, a crimped metal ribbon placed between the body and the gallery and adapted to be secured to the body and the gallery at alternate points.

4. The method of manufacturing galleryed articles of jewelry consisting in forming a body, a gallery and a bridging portion for the body and gallery, in separate parts, the parts being so related that when assembled the bridging portion will surround the body, and the gallery will surround the bridging portion, the bridging portion being provided with contacting points on one side thereof, securing such contacting points to the body, and with contacting points on the other side thereof, and securing such contacting points thereof to the gallery.

In testimony whereof, I have affixed my signature to this specification.

HENRY W. FISHEL.
